DESIGN FOR A BLOUSE

Irving Geist, New York, N. Y.

Application November 15, 1934, Serial No. 54,023

Term of patent 3½ years

To all whom it may concern:

Be it known that I, Irving Geist, a citizen of the United States of America, residing in Manhattan, county of New York and State of New York, have invented a new, original, and ornamental Design for a Blouse, of which the following is a specification, reference being had to the accompanying drawing, forming part thereof, wherein,

The garment of this case is characterized by the shirring where the sleeves join the body of the garment and by the setting of the sleeves over into the body.

I claim:

The ornamental design for a blouse, substantially as shown and described,

IRVING GEIST.
